UNITED STATES PATENT OFFICE.

EDWARD F. G. GIBBS, OF WASHINGTON, DISTRICT OF COLUMBIA.

HAND GRINDING-JIG.

1,120,926.

Specification of Letters Patent.

Patented Dec. 15, 1914.

Application filed October 24, 1913. Serial No. 797,107.

To all whom it may concern:

Be it known that I, EDWARD F. G. GIBBS, a citizen of the United States, residing at Washington, in the District of Columbia, have invented certain new and useful Improvements in Hand Grinding-Jigs, of which the following is a specification.

This invention relates to new and useful improvements in jigs, used for grinding cutters, known as "inserted cutters", by hand, to a given angle. I do not mean, however, to limit myself to grinding cutters only, or hand use only. It is hereinafter fully described, shown in the accompanying drawing, and then specifically defined in the appended claims.

The specific object of this invention is to obtain the design of a practical eye gaged and hand controlled jig, which can be manufactured economically and used satisfactorily in grinding internal and external inserted thread cutters to the proper angle on the face of a rotating grinding wheel; to grind such cutters to an equal angle on both sides, and with cross concave side faces; and for the further purpose of grinding and regrinding the top face of such cutters to a cross concave and to, what is known as, a "lip". To this end I have designed the mechanism illustrated in the accompanying drawing, which forms a part of this specification and in which drawing—

Figure 1 is a plan view of the jig, holding a cutter, which has just been ground by the grinding wheel shown. Fig. 2 is an edge view of the jig. Fig. 3 is a plan view of the cutter end of the jig, holding a cutter which is about to be cross concaved and lipped on top by a grinding wheel, shown. Fig. 4 is an edge view of the cutter-holding strap. Fig. 5 is a plan of the angle block, or angle piece. Fig. 6 is a front end view of the angle block. Fig. 7 is an edge view of the angle block, showing the triangular channel, and section of cutter therein. Fig. 8 is a plan view of an inserted cutter which has been ground. Fig. 9 is a side elevation of an inserted cutter which has been ground and lipped. Fig. 10 is a view of a cutter from the ground end. Fig. 11 is an angular side elevation of a cutter, as seen from a point in a line projected from one of the concaved angular cutting faces.

Reference now being had to the details of the drawing by letter, A designates the top and bottom frame pieces, or the frame. The

jig being skeleton in form and open-sided, there are no side frame pieces.

B designates the angle block or angle piece, carried between the frame pieces at their front end, the front end or front face, preferably of which, angle piece, carries the triangular channel or guide b, which channel or guide in fixed relationship to the frame governs the angle at which the cutter is ground. It also carries the rectangular channels, b², which are covered and protected by the frame pieces. C designates a cutter which is held in the said channel to be ground. D designates a grinding wheel with which the said cutter is ground.

E designates the strap the front end of which is inclined to agree with the incline of the channel, b, and having two arms, e, adapted to fit loosely in the rectangular channels, b², of the angle block. It embraces the said angle block, triangular channel and cutter in sliding relation thereto and holds the said cutter, while being ground. e² designates the rectangular union plug to which the rear ends of both arms are joined. Said strap is drawn against the cutter by F, the screw-threaded rod, and the nut f.

It is to be observed that when this jig is used as a hand jig, it is practically in the same plane with the axial center of the grinding wheel, horizontally disposed and the eye alone is used to gage the position of its rear end, both horizontally and vertically; the front end being supported by the rest carried by all hand grinders. It is adapted to eye gage and hand control, because it is long, slender, light and straight. It is of rectangular plan and cross-sectional figure, with no obstructions to distract the vision. Therefore it can be held at a right angle to, or square with the face of a grinding wheel, as shown in Fig. 1, with much greater accuracy than the cutter can be held at an angle of, say, 30 degrees. The vision is remarkably accurate in forming a right angle by intersecting one straight line with another, because in forming one right angle another is formed also, and comparison is natural. Furthermore the sides of the grinding wheel, which are at a right angle to its face, inform the operator when the jig is parallel therewith. And it is further to be observed that the function of the angle piece B, which may be integral with the frame, is to fix the proper angular rela-

- tionship between the cutter to be ground and the frame, so that when the frame is held at a right angle to the grinding wheel face the cutter is ground to the proper angle.
- 5 The function of the strap E is to maintain that relationship, by pressure, while the said cutter is being ground. In other words, it is to be seen that the channel, b, and strap, E, as applied, form an angular, contracting aperture, which both determines the angle of, and holds the cutter while being ground. It is also to be observed that both the diagonal angle, which gives the angle to the wall of the thread, and the vertical angle, which 10 gives clearance to the cutter, are obtained by eye gage and hand control of the jig. Note also that the protected strap, E, which embraces both the angle piece, B, and cutter, C, is far preferable to a yoke which would 15 penetrate the angle piece and embrace the cutter; for the reason that in grinding short cutters, in which the jig is most needed, the rear ends would be drawn into the hole in which the yoke worked.
- 20 25 It is quite possible and practicable, perhaps, to evade the exact construction shown here, eliminate the angle block and strap entirely, and substitute therefor, among other things, integral portions of the frame itself, 30 without deserting the principle of a fixed angular relationship between the cutter and frame. Against such infringement I desire to be protected, if I am the real inventor.
- When one side of a cutter held by the jig 35 is ground as shown in Fig. 1, the jig being held, by hand, or otherwise, the cutter is then turned upside down in the jig, and the jig turned upside down, and the operation repeated. The result is that the angle of 40 both ground faces are equal and correspond with the angle of the guide channel, b, of the angle block. The importance of equal angles is especially obvious in cutting internal threads.
- 45 From Figs. 4, 1 and 3, it is seen that the bottom, or front end of the strap, E, inside, is flat and vertically square with the frame, which keeps the square cutter, being ground, from turning upon its own axial center; 50 which, turning, would cause the clearance angles of the two sides to be ground unequal; while the face of the angle block, B, is provided with a triangular channel, b, which receives and holds a square cutter of 55 any size, within its range, so that its end cannot be drawn down by the grinding wheel. Furthermore, it is necessary for a jig of this nature to be of rectangular cross-sectional figure, or flat bottomed, in order to 60 sit steady on the grinder rest, and grind both sides equal. When a cutter has once been thus properly ground on its sides, it should be regarded as a formed cutter and sharpened when dull by grinding it on top 65 only, as shown in Fig. 3. Indeed, a cutter is

not ready for advantageous use until it is ground on top as shown in Fig. 3.

One great advantage incident to the use of this jig is that it aids the operator in holding the cutter practically in the same horizontal plane with, and vertically parallel to, the axial center of the grinding wheel, the face of which grinds it. Thus the ground faces are cross concaved slightly, by the curvature of the wheel, as shown in Figs. 70 75 8 9, 10, 11. Both sides of the two cutting edges being concaved they are particularly keen, cut rapidly and leave a smooth thread. Another advantage incident thereto, particularly noticeable in regrinding small 80 short cutters for internal thread cutting, is that it facilitates grinding what is known as "a lip on the cutter", as shown in Fig. 9. This jig is made in skeleton form, the framing and all parts being light, for the chief 85 purpose of making it as light and wieldy as practicable. It is made open-sided for the same reason and for the further purpose of enabling the operator to use common washers for clamps in clamping it to the table 90 of a cutter grinder, and thus clamp it without danger of crushing it. The presence of the union plug, e², makes the strap end less, and enables the applicant, at pleasure, to tap out the rod hole and convert the rod, F, and 95 nut, f, into a long thumb screw. The frame pieces of this construction also furnish the much needed cover and protection to the strap arms.

Having fully described my invention, I 100 desire to secure by Letters Patent what is new according to the following claims:

1. A thread-cutter grinding jig, adapted to eye-gage and hand-control; comprising a skeleton frame; an angle piece, carried by the said frame, adapted to receive a cutter to be ground and fix the specific angular relationship between it and the said jig; a strap embracing the said angle piece and cutter; and means for holding the said strap 105 against the said cutter while it is being ground; all substantially as set forth.

2. A thread cutter grinding-jig, adapted to eye-gage and hand-control; comprising an open-sided frame; an angle-piece carried by the said frame, adapted to receive a cutter to be ground and fix the specific angular relationship between it and the said jig; and means for holding the said cutter against the said angle piece while it is being ground; all substantially as set forth.

3. A thread-cutter grinding jig, adapted to eye-gage and hand-control; comprising a frame; an angle piece, carried by the said frame, having a channel in its front face 110 adapted to receive a cutter to be ground, having also side channels covered and protected by the said frame and adapted to receive the arms of a strap; a strap having 115 arms fitted to the said covered and protected 120 125 130

channels, in sliding relation thereto and embracing the said angle piece and cutter; and means for holding the said strap against the said cutter while it is being ground; all substantially as set forth.

4. A thread-cutter grinding-jig, adapted to eye-gage and hand-control; comprising a skeleton frame; an angle piece carried by the said frame adapted to receive a cutter to be ground; a strap, whose arms are covered and protected by the said frame, embracing the said angle piece and cutter; and means for holding the said strap against the said cutter while it is being ground; all substantially as set forth.

5. A thread-cutter grinding-jig, adapted to eye-gage and hand-control; comprising an open-sided frame; an angle piece carried by the said frame, adapted to receive a cutter to be ground; a strap, whose arms are covered and protected by the said frame, embracing the said angle piece and cutter; and means for holding the said strap against the said cutter while it is being ground; all substantially as set forth.

6. A thread-cutter grinding-jig, adapted to eye-gage and hand-control; comprising a skeleton frame; an angle piece, carried by the said frame, adapted to receive a cutter to be ground; a strap, whose arms are joined to a union plug at their rear ends,

embracing the said angle piece and cutter; and means for holding the said strap against the said cutter while it is being ground; all substantially as set forth.

35

7. A thread-cutter grinding jig, adapted to eye-gage and hand-control; comprising a frame; an angle piece, carried by the said frame, adapted to receive the cutter to be ground; a strap, whose arms are permanently joined and continuous at their rear ends, embracing the said angle piece and cutter; and means for holding the said strap against the said cutter while it is being ground; all substantially as set forth.

40

8. In a thread-cutter grinding jig, adapted to eye-gage and hand-control; the combination of a frame having flat top and bottom; an angle block carried by the said frame, having in its front face a triangular channel adapted to receive a cutter to be ground; a strap having a flat bottom, embracing the said angle block and cutter; and means for holding the said strap against the said cutter while it is being ground; all substantially as set forth.

50

In testimony whereof I affix my signature in presence of two witnesses.
